UNITED STATES PATENT OFFICE

THEO LANG, OF MUNICH, GERMANY, ASSIGNOR TO THE FIRM HANS TRINKL UHREN-
UND APPARATEFABRIK G. M. B. H., OF AUGSBURG, BAVARIA, GERMANY

CARTRIDGE CUT-OUT

Application filed August 7, 1925, Serial No. 48,828, and in Germany August 11, 1924.

This invention is a fuse plug and automatic cut-out having the form of a standard cartridge fuse. As the essential feature of the invention, the cartridge to be inserted is constructed as a permanent safety cut-out. A heating wire is wound around an insulating ring and insulating piece in such a manner that it depresses a hook-shaped spring, and the latter locks a contact bolt in the contact position.

Two embodiments of the invention are shown by way of example, in the accompanying drawings in which

Figs. 1 to 4 illustrate one construction, the cartridge being shown in Figs. 1 and 2 in longitudinal section on line A—B of Fig. 4 in the position ready for use and in the inoperative position respectively.

Fig. 3 is a cross section on line C—D of Fig. 1.

Fig. 4 is a cross section on line E—F of Fig. 2.

Figs. 5 to 9 illustrate a second construction, the cartridge being shown in Figs. 5 and 6 in longitudinal section respectively in the position ready for use and in the inoperative position.

Fig. 7 is a side elevation, the envelope being partly broken off.

Figs. 8 and 9 are cross sections on lines G—H of Fig. 5 and J—K of Fig. 6 respectively.

The casing 1 of the cartridge for cut-outs is made, as usual, of porcelain or of any other insulating material and carries on one end face a contact plug 2 and on the other end face a contact cap 3. The contact plug 2 is hollow and a spring 4 as well as a stud 5, controlled by said spring, are located in the hollow plug. A contact bolt 6 guided by a contact ring 7 fixed in the casing 1 is movably mounted in the casing 1 so that it bears against said stud 5.

An insulating ring 8 fixed on the one surface of the contact ring 7 accommodates in an axial groove 9 a locking spring 10 fixed on the contact ring 7 by a screw 11. This spring 10 is maintained under tension by a heating wire 13, through the intermediary of a pressure body 12 located in the groove 9 of the in-

sulating ring 8, said heating wire being wound several times around the insulating ring 8 and the pressure body 12. One end of the heating wire 13 is secured to the contact ring 7 by means of a bar 21 and the other end is secured to a bar 22 which is in turn connected to the cap 3. The locking spring 10 cooperates with a cut-out portion 14 of a disk 15 mounted on the contact bolt 6. Between disk 15 and contact ring 7 a pressure spring 16 is inserted which is wound around the contact bolt 6.

In the longitudinal bores of the rings 7, 8 a pin 17 is rotatably mounted which carries at one end a sickle-shaped disk 18 serving as a spark extinguisher. The other end of pin 17 is connected with a twisted bar 19, said bar projecting through a rectangular slot 20 of the disk 15 of contact bolt 6.

The operation of the cut-out is as follows:

The current flows from contact stud 2 through contact stud 5, contact bolt 6, contact ring 7, a contact bar 21, heating wire 13 and a contact bar 22 to the contact cap 3 (Fig. 1).

When short circuiting occurs or when the cut-out is overloaded in any other manner, the heating wire 13 is heated and expands, so that it no longer holds the spring 10 under the same tension as before. The locking spring 10 therefore releases the disk 15 of contact bolt 6. The bolt 6 moves toward the contact cap 3 under the action of spring 16 so that a gap is produced between the corresponding end of contact bolt 6 and stud 5. The electricity conducting connection between stud 2 and contact cap is interrupted (Fig. 2).

At the same time as the contact bolt 6 moves its disk 15 moves over the twisted bar 19 and turns this bar and the pin 17 on the same in such a manner that the disk 18 fixed on pin 17 is inserted between the contact bolt 6 and the contact stud 5 and extinguishes any spark and prevents the current passing from contact stud 5 to contact bolt 6 (Fig. 2).

When the several elements of the cut-out have to be returned into their operative position, it is only necessary to move the contact bolt 6 by hand or with the aid of any convenient instrument in opposite direction so that

the cut-out portion 14 of its ring 15 grips again behind the locking hook of spring 10 which, after the cooling of the heating wire, has returned into its locking position.

3 Simultaneously with the shifting of contact bolt 6, the bar 19, its pin 17 and disk 18 have been rotated in opposite direction so that the contact bolt 6 bears against the contact stud 5.

10 The safety cartridge according to the second form of construction shown in Figs. 5 to 9 comprises also an insulating casing 1, contact plug 2, contact cap 3, spring 4, stud 5 and contact bolt 6. This contact bolt 6 is 15 guided in a tube 23 fixed upon a plate 24 of insulating material carried by cap 3. On the other end of tube 23 a metal disk 25 is fixed. Underneath disk 25 a ring 26 of insulating material is fixed on the tube 23. A spiral 20 spring 27 wound around tube 23 bears with its upper end against ring 26 and with its lower end against a cross pin 29 movably guided in longitudinal slots 28 of tube 23 and fixed in the contact bolt 6, so that the 25 spring 27 has the tendency to permanently push the contact bolt 6 towards the contact cap 3. A spring 30, located in a longitudinal groove of the insulating body 26 has at its lower end a locking hook 31 which co-operates 30 with one end of a cross pin 29 fixed on contact bolt 6, the upper end of said spring being fixed on the disk 25 of tube 23 by means of a screw 32. The spring 30 is put under tension in the insulating body 26 with the aid 35 of an insulating piece 33 by a heating wire 34 wound several times around the insulating body 26, one end of said wire being electrically connected with the metal disk 25 and its other end being electrically connected 40 with a bar 36 fixed by a screw 35 on the insulating body 26. The free end of bar 36 bears against the metal cap 3 of the insulating casing 1 so that the electric connection with said cap is established.

45 In a longitudinal bore of disk 25 and of the insulating body 26 a pin 37 is rotatably mounted which carries at the upper end a disk 38 serving as spark extinguisher and which is connected at the lower end with a 50 twisted bar 39 having a longitudinal slot 40 with which engages the other end of cross pin 29 fixed in contact bolt 6.

The operation of the cut-out shown in Figs. 5 to 9 is similar to that of the cut-out shown 55 in Figs. 1 to 4. The current flows from contact plug 2 through stud 5, bolt 6, tube 23, metal disk 25, heating wire 34 and metal bar 36 to contact cap 3.

When short circuiting occurs or the cut-out 60 is otherwise over-loaded, the heating wire 34 is heated so that it expands and permits the spring which is under tension to move outwardly, and until the hook thereof releases the cross bolt 29 of spring controlled contact bolt 6. The bolt 6 is moved by the action of

spring 27 towards the contact cap 3. The electric connection between contact plug 2 and contact cap 3 is thus interrupted. The spark extinguisher 38 is rotated by means of the twisted bar 39 in the slot 40 of which the cross pin 29 of contact bolt 6 slides. The several elements are brought back into the operative positions by a pressure exerted upon bolt 6 by hand or by means of a needle.

1 claim:

1. A cartridge having contacts at opposite ends thereof and a cut-out therein including a spring actuated contact bolt, a spring actuated locking hook for securing said bolt in contact position, a block of insulating material in which said contact bolt is guided, and a heating wire wound around said block of insulating material and controlling said locking hook.

2. A cartridge having contacts at opposite ends thereof, a spring controlled contact bolt in said cartridge, a spring controlled locking hook for securing said bolt in contact position, an insulation member in which said contact bolt is guided, and a heating wire inserted in the main circuit and controlling said locking hook, said wire being wound around said insulation member.

3. A cartridge having a pair of relatively movable contact members, a block of insulating material within which one of said members is slidable, a spring normally tending to separate said members, a hook for normally preventing said separating movement, and a heating wire wound around said block of insulating material and normally holding said hook in operative position, said wire being connected in circuit and expanding to release said hook upon excessive flow of current.

4. A cartridge having a permanent cut-out therein, including a longitudinally slidable contact member, a block of insulating material for guiding said member, a spring normally tending to push said member to open circuit position, a hook for preventing such movement, and a heating wire having one end connected to said contact member, and the other end to the end of said cartridge, said wire being wound around said block of insulating material and normally holding said hook in operative position.

5. A cartridge having a foot contact, a slideable contact bolt, a spring normally holding said foot contact and said contact bolt in engagement, a disk pivoted to swing in a plane at right angles to the direction of movement of the contact bolt, and a member connected to said contact bolt and having lost motion connections with said disk for swinging the latter upon the endwise movement of said bolt.

6. A cartridge for cut-outs which is constructed as permanent safety device comprising a spring controlled contact bolt, a cross

pin on said contact bolt, a metal tube enclosing said contact bolt and having longitudinal slots with which said cross pin of said contact bolt engages, and an oscillatory circuit breaking member operatively connected to said cross pin.

7. A cut-out device comprising a tubular insulating casing, a longitudinally movable circuit breaking member normally tending to move to open circuit position a catch within said casing, and normally holding said member in closed circuit position, and movable radially of the casing to release said member, and a coil of wire normally in circuit and normally holding said catch in operative position, said coil being expansible when heated, to release said catch.

8. A cut-out device comprising a tubular insulating casing, terminal members at opposite ends thereof, a movable circuit breaking member, a spring catch extending lengthwise of said casing within the latter and normally holding said member in closed circuit position, and a wire wound helically within said casing and normally holding said catch in operative position, said wire being expansible radially to release said catch when heated by excess current.

9. A cut-out device including a tubular insulating casing, an annular insulation member disposed therein, a contact member movable longitudinally through said insulation member, a spring catch extending lengthwise of said insulation member upon the exterior thereof, and normally holding said contact member in closed circuit position, a coil encircling said insulation member and insulated from said spring catch and normally holding the latter in operative position, said coil being expansible when heated to release said spring catch.

10. A cut-out device comprising a tubular insulating casing, a contact member movable longitudinally thereof, a disk carried by said member, a spark arrester movable transversely of the path of movement of said contact member, and an oscillating support for said spark arrester, said support having engagement with said disk and adapted to be rotated upon the longitudinal movement of the disk with said contact member.

11. A cut-out device comprising a tubular insulating casing, a circuit breaking member disposed therein, a spring catch for normally holding said member in closed circuit position, and a coil of wire insulated from said catch but normally holding the latter in operative position, said coil being expansible when heated to permit swinging movement of said catch and the release of said contact member.

In testimony whereof I affix my signature.
THEO LANG.
